UNITED STATES PATENT OFFICE

WILLIAM CALLAWAY, OF WICHITA, KANSAS.

WIRE-HOLDING CLIP.

1,206,812.

Specification of Letters Patent.

Patented Dec. 5, 1916.

Application filed February 25, 1914. Serial No. 821,032.

To all whom it may concern:

Be it known that I, WILLIAM CALLAWAY, a citizen of the United States, residing at Wichita, in the county of Sedgwick and State of Kansas, have invented certain new and useful Improvements in Wire-Holding Clips, of which the following is a specification.

This invention relates to a wire-holding clip, and the principal object of the invention is to provide a clip which can be formed from a sheet metal blank, and which may be so constructed that it may be used in connection with either fence posts of the wooden type or of the cement type.

Another object of the invention is to so construct the clip that the wires forming a fence may be securely connected with the fence post and to permit the wires to be released from the post when it is desired to lower the wires.

This invention is illustrated in the accompanying drawings wherein—

Figure 1 is a view showing the post in vertical section and the clip in side elevation; Fig. 2 is a top plan view of the clip; Fig. 3 is a view of the blank from which the clip shown in Figs. 1 and 2 is formed; Fig. 4 is a view showing a post in transverse section and a modified form of clip in top plan; Fig. 5 is a side elevation of the clip shown in Fig. 4; Fig. 6 is a view of the blank from which the clip shown in Figs. 4 and 5 is formed.

The clip shown in Figs. 1, and 2 is formed from a blank shown in Fig. 3. This blank which is formed from resilient sheet metal is provided with arms 10 and 11 and tongues 12 and 13 which arms and tongues extend from opposite sides of the body portion 14 of the blank. These arms and tongues are bent along the dotted lines 15 and 16 so that the arms 10 and 11 will extend in opposite directions from the tongues 12 and 13. The arms 10 and 11 are tapered and have their edges provided with notches forming teeth 17 which will lock the arms in the post 18 and thus prevent the clip from becoming detached from the post. This form of clip can be used with either the cement or the wooden type of post since the pointed arms can be easily driven into the wooden post and the teeth 17 will securely hold the arms in the cement post. The tongues 12 and 13 are bent to extend in overlapped relation as shown in Figs. 1 and 2 with the tongue 13

extending within the tongue 12 and having its inner end portion bent to form a hook 19 upon which the wire 20 is intended to rest.

The form of clip shown in Figs. 4 and 5 is formed from the blank shown in Fig. 6. This blank comprises the body portion 21 from which there extend the arms 22 and tongues 23 and 24. The arms 22 which are provided with longitudinally-extending slots 25 are bent to extend in opposite directions from the tongues 23 and 24 and have their inner end portions bent to form hooks 26 which securely hold the clip in the post. This form of clip is only intended to be used in connection with the cement type of post. The tongues 23 and 24 are bent to extend in overlapped relation with the tongue 24 extending behind the tongue 23 so that the fence wire may be securely connected with the post by being passed through the eye 27 formed by the tongues 23 and 24 and engaged by the hook at the lower end of the tongue 24.

The operation of this clip is as follows: After the posts have been put in the ground, the wires are connected with the clips. The clips shown in Figs. 1 and 2 may be placed in the posts when the posts are being formed or may be driven into the wooden posts by a suitable tool such as a hammer, but the clips shown in Figs. 4 and 5 may be placed in the posts when forming the posts. When the clips shown in Figs. 1 and 2 are used, the wires are passed between the tongues 12 and 13 and are then raised so that they will rest upon the hooks 19. It should be noted that if desired ends of the tongues 13 and 24 may be beveled so that while it will be easy to insert the wires, it will be difficult to remove them. The wires can now be tightened and will be securely held in the desired positions thus forming the fence. If it is desired to lower the wires so that a wagon or animals such as cattle or horses can be driven from one field to another, the wires are raised slightly and after being passed beneath the hooks 19, are raised so that they will pass through between the tongues 12 and 13. The wires can then be lowered so that they will rest close to the ground and the wagon or animal can be driven over the wires. The wires can then be raised and again used with the clips and the fence will be in its original condition. In the form shown in Figs. 4 and 5 the op-

eration is very similar to that shown in Figs. 1 and 2. In this form the wires are passed between the tongues 23 and 24 and will then extend through the eyes 27 where it will be engaged by the hook at the lower end of tongue 24. When it is desired to release the wires, they are passed out between the tongues 23 and 24 and can then be lowered to rest close to the ground. It will thus be seen that the operation of these two types of clips is very similar, the only difference between the two being the form shown in Figs. 1 and 2 which is the hook 19, and the one shown in Figs. 3 and 4 which is provided with the slotted arms 22 instead of being provided with the tapered arms 10 and 11.

What is claimed is:

A clip for supporting a strand of wire

formed from a sheet metal blank comprising a body portion having means for connecting the clip with a post, and upper and lower resilient tongues extending from said body portion, the upper tongue being bent downwardly in spaced relation to the body portion and having its free end portion bent inwardly to form a wire supporting hook extending in close proximity to said body portion, the lower tongue being bent upwardly outside the upper tongue and extending in overlapping relation to the same

In testimony whereof I affix my signature in presence of two witnesses.

WILLIAM CALLAWAY.
